CONTROL AND SIGNAL MEANS FOR MOTOR DRIVEN MACHINES

Edward Q. Mead, Milwaukee, Wis., assignor to Cutler-Hammer, Inc., Milwaukee, Wis., a corporation of Delaware

Application June 25, 1952, Serial No. 295,575

6 Claims. (Cl. 340—267)

This invention relates to controllers for motor driven printing presses and other machines, and more particularly to controllers embodying signaling means.

Controllers for large printing presses are commonly required to afford signaling sufficiently in advance of starting whether for inching, threading or running to enable the workmen who may be working on the press to protect themselves. Only a short signal period is necessary and it is often important to avoid needless delay in starting.

The present invention has among its objects to provide a controller affording the protection aforementioned, and at the same time affording other desirable operating characteristics.

Another object is to provide a controller of the aforementioned character not only having improved operating characteristics but having also relative simplicity of construction and of wiring.

Another object is to provide a controller affording the aforementioned safe feature and improved operating characteristics as functions of depression of certain of the pushbutton switches now commonly employed in printing press controllers.

Other objects and advantages of the invention will hereinafter appear.

In accordance with the present invention as applied to a printing press drive having a relatively small motor for inching, threading and slow speed running and a relatively large motor for high speed running, it is proposed to equip the controller with the usual control instrumentalities including separate pushbutton switches for inching and running. In accordance with the preferred form of the invention it is proposed to provide means whereby depression of either the inch or run buttons will result in both visual and audible warning signals followed by the respective inching or running operation a predetermined time following such depression. It is proposed to have the signalling terminated at the time that the inching or running operation is commenced. It is intended to automatically provide such characteristics following the above-mentioned depression of the inch or run buttons. It is further proposed to provide the above-mentioned predetermined time interval by means of certain electromagnetic timing relays. Of course recitation of these specific proposals is not to be regarded as limiting the present invention thereto or as setting forth in full the desirable operating characteristics contemplated.

The novel features which I consider characteristic of my invention are set forth with particularity in the appended claims. The invention itself, however, both as to its organization and its method of operation, together with additional objects and advantages thereof, will best be understood from the following description of a specific embodiment when read in connection with the accompanying drawings, in which—

Figure 1 is an across-the-line diagram of the controller;

Fig. 2 is a chart showing vertically aligned each coil and its respective contacts of Fig. 1.

2

Similar reference characters indicate corresponding parts throughout the several views of the drawings.

First referring to Fig. 2, it will be observed that the controller has certain switches and a number of relays having contacts as follows:

- LM relay having a winding 1 and a set of three normally open contacts 1^a;
- SM relay having a winding 2 and a set of three normally open contacts 2^a and normally open auxiliary contacts 2^b;
- A normally open limit switch 3 and a normally closed limit switch 4, each responsive to operation of either the LM or SM relays;
- 2TR relay having a winding 5 and normally open contacts 5^a provided with instantaneous closure and timed opening;
- 1TR relay having a winding 6 and normally open contacts 6^a provided with instantaneous opening and timed closure;
- Inch relay having a winding 7, normally closed contacts 7^a and 7^b, and normally open contacts 7^c and 7^d;
- Safe relay having a winding 8 and normally open contacts 8^a and normally closed contacts 8^b;
- Signal relay having a winding 9 and normally open contacts 9^a and normally closed contacts 9^b;
- Stop relay having a winding 10 and normally closed contacts 10^a and two normally open contacts 10^b and 10^c;
- ON-1 relay having a winding 11 and normally open contacts 11^a;
- An off relay having a winding 12 and normally open contacts 12^a;
- A 1CR relay having a winding 13 and normally open contacts 13^a and 13^b;
- And an On relay having a winding 14 and normally closed contacts 14^a and normally open contacts 14^b and 14^c.

Referring to Fig. 1, the relays LM and SM respectively control energization of a large motor and a small motor (neither being shown) for the purpose of operating the press (also not shown).

As will be understood, the press drive will comprise either D. C. or A. C. motors, whereas it is assumed that the motors are A. C. and of the three phase type, wherefore both switches are shown as of the triple pole type.

The system illustrated comprises in addition to the aforementioned switches and relays a crosshead type controller 26 to be operated by a pilot motor M having an armature a and series field windings f and f¹, to be excited selectively to effect reverse operations of the motor and hence reverse operations of the crosshead arm 26^a of the controller 26. Use of such a crosshead type of controller for a double motor drive for printing presses whether A. C. or D. C. has been common practice for such a long period that both the motor connections and resistances have been omitted, the crosshead controller being shown only as provided with those connections required for the LM and SM switches and the pilot motor. As will be understood, the crosshead has a position—shown as its extreme left-hand position—in which it enables the SM switch to be energized for inching, whereas the crosshead is movable from such position through the medium of the pilot motor M to other positions first to establish running connections for the small motor and then to start the large motor and to regulate the speed of the latter.

The pilot motor M is controllable for shifting the crosshead arm 26^a to select the positions through the medium of the aforementioned "on" and "off" relays 14 and 12 which in turn are controllable by "on" and "off" pushbutton switches 15 and 16, shown and so labeled in Fig. 1.

Further, referring to Fig. 1, the same also shows an

"inch" pushbutton switch 17, a "stop" pushbutton switch 18, and a "run-safe" pushbutton switch 19. Fig. 1 also shows the usual limit switches 3 and 4, operatively associated with switches SM and LM as depicted in Fig. 2. Limit switch 3 is normally open while limit switch 4 is normally closed, but both are jointly operable by either switch SM or switch LM. The arrangement is such that operation of either of said motor switches closes switch 3 and opens switch 4.

The signaling means shown in Fig. 1 comprises signal lights 20 controlled by a flasher 21 comprising a motor 21^a and contacts 21^b, and also a bell 22. The flasher and the bell are controlled by contacts 9^b and 9^a, respectively, of the signal relay.

To inch the press when the crosshead arm 26^a is in the position shown and when all of the switches and relays are deenergized, the inch button 17 is depressed. The operation is very simple and expeditious, but so many circuits are involved that the cycle will be described as follows:

When the inch pushbutton switch 17 is depressed a circuit is completed to the 2TR relay through said button 17, winding 5 and the normally closed contacts 14^a and 8^b. Energization of winding 5 causes contacts 5^a to close, thereby energizing the 1TR winding 6 and the signal winding 9. Said signal winding is energized through a circuit consisting of said contacts 5^a, the normally closed inch contacts 7^a, the normally closed on contacts 14^a, and the normally closed safe contacts 8^b. Energization of signal winding 9 affords power connections to the bell 22 by virtue of closure of the normally open contacts 9^a. Such energization also opens the normally closed signal contacts 9^b, thereby removing the signal lights 20 from across the line and making such lights dependent upon closure of contacts 21^b which, as above mentioned, is controlled by motor 21^a. It is believed apparent that Fig. 1 clearly shows the cam arrangement whereby continued energization of motor 21^a causes contacts 21^b to be alternately closed and opened, thereby affording interrupted energization of the signal lights 20.

The aforementioned energization of the 1TR coil 6 causes contacts 6^a to begin timed closure. The mechanism for affording contacts 6^a with timed closure is shown in Fig. 2 to consist of a dashpot 6^b which is, of course, only illustrative, it being fully realized that there are many forms of timing structures which could be used for this purpose. When said contact 6^a finally closes, the inch winding 7 is energized by the virtue of a circuit including the inch button 17, said contacts 6^a, and the normally closed safe contacts 8^b. Energization of the inch winding 7 causes the normally closed inch contacts 7^a and 7^b to open and the normally open inch contacts 7^d and 7^c to close. Opening of contacts 7^a removes power from the signal winding 9, thus causing the power to be removed from the bell 22, and the signal lights to be continuously energized by virtue of closure of contacts 9^b. Simultaneous with such deenergization of the bell 22, is energization of the stop winding 10, due to closure of the inch contacts 7^d. Energization of stop winding 10 closes the normally open contacts 10^b which together with contacts 7^c, now closed by virtue of energization of winding 7, affords energization of the SM switch through said contacts 7^c and 10^b, the crosshead arm 26^a and winding 2. Energization of winding 2 causes contact set 2^a to close, thus completing power connections to the small motor (not shown) and hence causing the presses to rotate slowly (also not shown).

Said inching operation will continue until the inch button 17 is released, thereby causing deenergization of the inch winding 7, which in turn causes the SM switch to be deenergized due to return to normally open position of the inch contacts 7^c. Return to the normally closed position of inch contacts 7^a causes reenergization of the signal winding 9, thereby effecting power connections to the bell 22 and intermittent operation of the signal

lights 20, caused respectively by closure of contacts 9^a and opening of contacts 9^b. Said visual and audible signaling will continue until the 2TR contacts 5^a time open, the 2TR coil 5 having been deenergized by virtue of release of pushbutton 17. If the inch button 17 is depressed before the 2TR contacts 5^a have timed open and terminated the signaling, the inch coil 7 will be immediately energized since the 1TR contacts 6^a are still closed. Thus a second inching operation will be commenced without the aforementioned time delay. Such operation is very advantageous in that it enables the operator to effect rapid successive inching operations without needless signaling and time delays. Should an inching operation be desired after the 2TR contacts 5^a have timed open, depression of the inch button 17 will instigate the signaling and delayed inching operation as above explained. This results due to the time interval necessary to close contacts 6^a. When said contacts 5^a finally open, all of the windings are deenergized.

20 The stop winding 10 has been deenergized due to closure of the inch contacts 7^b which short out power to said winding 10, thus interrupting the maintaining circuit for said winding which was previously afforded by stop contacts 10^c.

Due to the above mentioned deenergization of the SM switch, power connections to the small motor are disconnected, thereby permitting the press to come to rest.

To run the press in its normal manner, the on pushbutton switch 15 is depressed and subsequently released 30 when the desired press speed has been obtained. The "normal run" cycle also will be described fully, it being assumed that the several switches and relays occupy the respective positions illustrated in Fig. 1.

Depression of the on pushbutton switch 15 energizes 35 the ON-1 relay winding 11 through a circuit composed of switch 15 and contacts 14^a and 8^b. Energization of winding 11 closes the normally open ON-1 contacts 11^a, thereby energizing the 2TR winding 5. Energization of winding 5 immediately closes the normally open 2TR contacts 5^a, thereby instigating the audible and visual signaling as precedes the above explained inching operation. As soon as the 1TR contacts 6^a time closed, the inch winding 7 is energized and the signaling operations are terminated by virtue of opening of contacts 7^a. As 45 above explained, closure of contacts 7^d energizes the stop winding 10 and cause contacts 10^b to close; said contacts 10^b together with the inching contacts 7^c effect energization of the SM winding 2, thereby causing the small motor to operate. Energization of winding 2 causes the normally open auxiliary contacts 2^b to close, thereby energizing the ON winding 14 through a circuit consisting of switch 15 and contacts 2^b and 8^b. Energization of winding 14 opens contacts 14^a and closes contacts 14^b and 14^c.

Opening of contacts 14^a affords deenergization of the 50 2TR winding 5, thereby permitting the 2TR contacts 5^a to time open during energization of winding 14, thus insuring the elimination of signaling following "normal running" of the presses. Said opening of contacts 14^a also affords deenergization of the ON-1 winding 11. 55 Closure of contacts 14^c affords continued energization of the inch winding 7 after the 1TR winding 6 has been deenergized by virtue of the timed opening of said contacts 5^a. The limit switch 3, in series with the normally open on contacts 14^b and the field winding f of the pilot motor M, is now closed due to the aforementioned energization of winding 2. As above noted said limit switch 65 3 is responsive to energization of either the SM or LM switches. Such closure of limit switch 3 together with closure of contacts 14^b affords energization of the field winding f, causing the pilot motor M to operate to effect movement of crosshead arm 26^a from its extreme left hand position. The aforementioned energization of winding 2 has caused energization of the small motor, thus causing the presses to operate slowly.

75 As the crosshead 26^a moves to the right, the small motor

increases in speed until a point 26^b is reached, at which point the 1CR winding 13 becomes energized by virtue of the circuit completed through limit switch 3, members 26^c and 26^d of crosshead 26, and contacts 10^b. Energization of winding 13 closes the normally open contacts 13^a, thereby affording energization of the LM winding 1. Energization of winding 1 closes contact set 1^a thus affording power to the large motor (not shown). The small and large motors are so constructed that when the large motor is energized the small motor is automatically de-energized due to mechanical interlocks therebetween. The presses are thus rotated by virtue of energization of the large motor which increases in speed until the on pushbutton 15 is released or until the crosshead 26^a reaches the extreme right hand position.

Should it become desirable to increase the speed of the presses while the crosshead 26^a is in an intermediate position, such change in speed can be effected by depressing the on switch 15. Such closure of switch 15 re-energizes winding 14 thereby closing contacts 14^b and effecting energization of the field winding f of motor M, causing arm 26^a to be moved to the right.

Closure of the off pushbutton switch 16, on the other hand, effects energization of the off winding 12 which causes contacts 12^a to close, thereby effecting energization of field winding f¹ and causing arm 26^a to move from the right to the left, decreasing the rotational speed of the presses. Release of the off pushbutton switch 16, of course, effects deenergization of said winding 12, opening the contacts 12^a and removing power from the pilot motor M.

When it is desired to bring the presses to rest, it is only necessary to momentarily close the stop pushbutton switch 18. Such closure effects deenergization of the stop winding 10 causing contacts 10^a to return to closed position, thereby effecting energization of the off winding 12. Deenergization of the stop winding 10 also causes contacts 10^b to open the circuit to windings 2 and 13 thus removing power connections from all of the press motors. The presses are thus brought to rest. Energization of the off winding 12 causes closure of contacts 12^a thereby effecting energization of the field winding f¹ which causes the pilot motor M to move the crosshead arm 26^a into its extreme left hand position. When such extreme left hand position is reached, the off winding 12 is deenergized by virtue of a conventional limit switch (not shown), in circuit with said off winding 12 and operable by virtue of movement of arm 26^a into its extreme left hand position. Thus the controller is completely deenergized.

If it is desired to effect threading of the presses it is merely necessary to maintain the on switch 15 depressed until arm 26^a moves into the position whereby winding 2 is energized through a circuit consisting of limit switch 3, arm 26^a, the winding 2, and contacts 10^b. At this point the on button 15 can be released to effect slow threading operation of the presses by virtue of the continued energization of the small motor. From this position the presses may be varied in speed or completely shut down as above explained for the "normal run" operation.

When at rest the press may be made safe by closing the run-safe switch 19. Such closure energizes winding 8 thereby opening contacts 8^b and causing inch switch 17 and run switch 15 to be inoperative. Energization of winding 8 also effects closure of the normally open safe contacts 8^a thus affording continuous energization of the safe lights 23. Before the presses can be operated again, the run portion of the run-safe switch 19 must be depressed. This, of course, removes power from the safe lights 23 and closes contacts 8^b, thereby setting up the energizing circuit for winding 7 so that subsequent closure of either inch switch 17 or on switch 15 will effect energization of said inch winding 7 as heretofore explained.

It is thus apparent that signaling will be effective before inching, running or threading operations.

Although I have shown and described a specific embodiment of my invention, I am fully aware that many modifications thereof are possible. My invention, therefore, is not to be restricted except insofar as is necessitated by the prior art and by the spirit of the appended claims.

I claim:

1. In a safety controller for an electric motor, in combination, an electric motor, a time delay starting circuit and warning signal means, said circuit comprising a starting switch and first and second electrically energizable timing relays having timed closing and timed opening contacts respectively and starting means for said motor comprising the contacts of said first relay and said starting switch, the contacts of said second relay being in the energizing circuit of said first relay, and said signal means being responsive to actuation of the contacts of both of said timing relays.
2. In an electric motor controller, in combination, a starting switch, a first timing switch operative after a predetermined interval following energization thereof to actuate its contacts, a second timing switch operative after a predetermined interval following deenergization thereof to actuate its contacts, an electric motor, means including said starting switch and contacts of said first timing switch for energizing the motor, an energizing circuit for said first timing switch comprising contacts of the second timing switch, and an energizing circuit for the second timing switch comprising said starting switch.
3. In a motor controller for inching operation of an electric motor, energizing means for the motor comprising an inching switch and means to render said energizing means ineffective for a predetermined time following actuation of said inching switch, and means to maintain said energizing means effective for a predetermined period following cessation of an inching operation of the motor.
4. In a controller for safely inching an electric motor, in combination, an electric motor, electro-responsive means to energize the motor, energizing means for said electro-responsive means comprising an inching switch and means responsive to actuation of the inching switch to prevent energization of the electro-responsive means for a predetermined period following actuation of the inching switch and to permit energization of the electro-responsive means during a predetermined interval following actuation of said inching switch whereby successive inching operations may be commenced without time delay only if commenced within a predetermined interval following a previous inching operation.
5. The combination defined in claim 4, including safety signalling means and means including said inching switch to initiate signalling thereby, and means to terminate said signalling during periods in which said motor is inched.
6. In a safety controller for an electric motor, in combination, an electric motor, an inching switch for affecting inching operation of the motor, means responsive to actuation of the inching switch to prevent inching operation of the motor during a given interval following actuation of the inching switch, and means to permit inching operation of the motor in response to actuation of the inching switch during a given period following an actuation of the inching switch, whereby successive inching operation may be commenced without delay only if commenced within a given period following a previous inching operation.
